UNITED STATES PATENT OFFICE.

CHARLES C. SPREEN, OF DETROIT, MICHIGAN.

MECHANICAL REFRIGERATION.

Application filed January 29, 1927. Serial No. 164,426.

My invention relates to mechanical refrigeration, and particularly to refrigerant expansion apparatus especially designed for domestic mechanical refrigerating units, and 5 the principal object of my invention is to provide new and improved apparatus of this type. In the drawings accompanying this specification and forming a part of this application I have shown, for purposes of illustration, one 10 form which my invention may assume, and in these drawings:

Figure 1 is a front elevation showing the embodiment of my invention disclosed herein, while

15 Figure 2 is a section on the line 2—2 of Figure 1.

The embodiment of my invention herein shown comprises a refrigerator cabinet 11 having a refrigerating compartment 12 which 20 houses an expander 13 consisting of a plurality of substantially identical units 14 each comprising a pair of spaced headers 15 having in opposed faces a plurality of apertures 16 designed to receive the ends of the cross tubes 25 17 which connect the headers together in spaced relation to each other.

In order to maintain the pipes in spaced relation as well as to increase the refrigerating effect of the unit the pipes 17 of each unit are 30 provided with a multiplicity of plate-like fins 18 having perforations permitting them to be slipped onto the pipes in such manner that they will be disposed at right angles to the axes of the pipes 17.

35 One of the headers 15 of the top unit 14 is connected to the refrigerant inlet valve 19 of the refrigerating system, the remaining headers 15 are connected together by pipes 20 in such manner that the assembled units form a 40 single refrigerant expansion chamber, and the remaining header 15 of the unit farthest removed from the unit 14 connected to the inlet valve 19 is connected by a pipe 21 to the compressor of the system, not shown.

45 The several units are connected together in spaced relation by supporting means consisting of a plurality of brackets 22 attached to the top wall 23 of the compartment 12 by means of bolts 24, and each consisting of a 50 metal strap bent upon itself and provided at spaced intervals with loops 25 adapted to engage the ends of the headers 15.

The edges of the fins 18 engage and support sleeve-like receptacles 26 adapted to receive 55 ice trays 27.

From the above disclosure it will be obvious

to those skilled in the art that I have provided a refrigerant expansion unit which may be used in varying numbers to form a refrigerant expansion apparatus of any desired size and 60 capacity.

At the same time it will be obvious to those skilled in the art that the embodiment of my invention herein shown and described may be variously changed and modified without departing from the spirit of the invention or sacrificing the advantages thereof, and it therefore will be understood that the disclosure herein is illustrative only, and that my invention is not limited thereto.

70 I claim:

1. Refrigerant expansion apparatus comprising: a plurality of refrigerant expansion units formed substantially identical, and each comprising a refrigerant expansion compartment, consisting of a pair of headers with connecting tubes; fin means on said connecting tubes; ice tray receptacles carried by said fin means; a framework connecting said refrigerant expansion compartments into a single 75 refrigerant expansion unit; and conduits connecting said headers into a single refrigerant expansion chamber.

2. Refrigerant expansion apparatus comprising: a plurality of refrigerant expansion 80 units formed substantially identical, and each comprising a refrigerant expansion compartment, consisting of a pair of headers with connecting tubes; fin means on said connecting tubes; ice tray receptacles carried by said fin 85 means; a framework connecting said headers into a single refrigerant expansion unit; and conduits connecting said headers into a single refrigerant expansion chamber.

3. Refrigerant expansion apparatus comprising a plurality of refrigerant expansion units formed substantially identical, and each including a refrigerant expansion compartment consisting of a pair of headers with connecting tubes, fin means on said connecting tubes, ice tray receptacles carried by said fin means, said ice tray receptacles being arranged in thermal contact with the fins on adjacent tubes of adjacent expansion units, a framework connecting said refrigerant expansion compartments into a single refrigerant expansion unit, and conduits connecting said headers into a single refrigerant expansion chamber.

110 In testimony whereof I hereunto affix my signature.

CHARLES C. SPREEN.
